IMPROVED ANVIL FOR SWEDGING CALKS FOR HORSE-SHOES.

PETER BADORE, OF MONTPELIER, VERMONT.

Letters Patent No. 60,610, dated December 18, 1866.

The Schedule referred to in these Letters Patent and making part of the same.

TO ALL WHOM IT MAY CONCERN:

Be it known that I, PETER BADORE, of Montpelier, in the county of Washington, and State of Vermont, have invented a new and useful improvement in Dies for forging and shaping steel bars for the Toe Calks of Horse-Shoes; and I do hereby declare that the following is a full, clear and exact description thereof, which will enable others skilled in the art to make and use the same; reference being had to the accompanying drawings, forming part of this specification, in which—

Figure 3 is a perspective view of the swedge for drawing the steel to an edge for forming the calks, showing, in red lines, a piece of steel in place.

Figure 4 is a vertical cross section of the same.

Similar letters of reference indicate like parts.

My invention has for its object to furnish wedges, by the use of which the steel may be drawn to an edge quickly and uniformly, for forming toe calks for horse-shoes.

A is the swedge for drawing the steel to an edge and into proper shape for forming the toe calks. Upon the lower side of the plate a^1 of the swedge A is formed a shank a^2 , which fits into a hole in the anvil in the ordinary manner. Upon the upper side or face of the plate a^1 is formed a groove or longitudinal notch, having the exact form which it is desired that the steel should have when drawn to an edge for forming the calks. The calks are then formed and connected to the shoe for heating and welding in the ordinary manner.

What I claim as new, and desire to secure by Letters Patent, is—

The swedge A for drawing the steel from which the toe calks are to be formed to an edge, when said swedge is constructed substantially in the form herein shown and described.

PETER BADORE.
